UNITED STATES PATENT OFFICE.

WASSYL ORLOWSKY, OF HABANA, CUBA.

LIFE-SAVING DEVICE FOR SUBMARINE VESSELS.

Application filed October 28, 1926. Serial No. 145,893.

The invention relates to improvements in attachments to submarine vessels and its object is to provide a simply constructed device, whereby the entering and leaving the body of the vessel, while submerged, is possible for the entire crew.

In the present types of submarine vessels, when some part is damaged, so that it cannot rise to the surface, the crew perishes. The existing life saving implements present a difficulty in that they interfere with the offensive power of the submarine, they take up too much space and in the event of the submarine being damaged and unable to rise, only a few of the crew can escape.

The present invention enables the entire crew of the submarine vessel to leave and enter the vessel while the submarine is submerged, either singly or together, as the circumstances demand, taking up no valuable space in the submarine, nor injuring the aggressive power, but on the contrary increasing it. The entrance or exit even for the entire crew is not difficult even if it is necessary to repeat this operation several times.

With these and other objects in view the invention has certain novel features of construction as hereinafter shown and specifically pointed out in the claim and the drawings illustrative of the embodiment of the invention.

Fig. 1. is a central longitudinal section of the middle part of the submarine vessel showing the compartments and passage through which the operators leave and enter the hull of the vessel with the improvements embodied therein.

Fig. 2. is a transversal section on the line 2-2 of Fig. 1.

Fig. 3. is a plan view in section on the line 3-3 of Fig. 1.

The hull of the submarine vessel is represented at 1, compartment 2 is the conning tower which is also designed for the entrance and exit for the entire crew, and is connected with the diver's compartment 3 by the door 4 which is held on the hook 5 when it is opened.

Below the compartment 2 is the main compartment of the submarine vessel 7, they are both connected by means of the door 8 under which is a ladder 9. The diver's compartment 3 is arranged for the operations of divers singly; under compartment 3 is the passage 10 and communicating therewith by

means of a hatch door 11. The doors 4, 6, 8 and the hatch door 11 are arranged to swing on hinges 12, and are firmly closed with the aid of screws 13. The passage 10 has a ladder 14, on which the operators go out to the deck of the submarine vessel or to the sea bottom.

15 is a metallic tank for the storage of compressed air supplied by an electric operated compressor 16 in compartment 7.

From the tank 15 the compressed air goes out through the pipe 17 into the compartments 2, 3 and into the passage 10, the pressure of the air being regulated by taps; the compartment 2 by the tap 18, compartment 3 by the tap 19, the passage 10 by the tap 20.

Manometers 21 arranged in compartments 2 and 3 show the air pressure required to make possible the escape of the entire crew of the vessel under water.

From the passage 10 the pipe 22 leads to the manometer 23 which shows the pressure of the water in the passage 10. The compartments 2, 3 and 7 are connected with each other by the pipes 24, which have taps 25, which serve for regulating the pressure of the air in all compartments of the submarine vessel, and in this way facilitate the opening of the doors 4 and 8, for the operators to enter into the submarine.

When the submarine vessel is in action the doors 4 and 8 are always open so that it makes possible to use compartments 2 and 3 for any purpose.

The hatch 11 is always solidly closed so that no water can enter the interior of the submarine.

In operating the improved device, when it becomes necessary for one or a few persons to leave the vessel (this depends on the capacity of the diver's compartment 3) the divers enter compartment 3 by the ladder 9, open the tap 20, blowing out the passage 10 and then close the tap 20, a manometer 23 showing what pressure is required in compartment 3 so that the water will not enter, when the hatch 11 is opened.

Then on closing door 4, the divers open tap 19 and when the manometer 21 shows the same pressure of the air as manometer 23, close tap 19, open hatch 11 and move down the ladder 14 into the passage 10 leading from the deck of the submarine vessel to the sea bottom.

If it is necessary for the entire crew to

leave the vessel at once, they gather in compartment 2 and 3, blow out the passage 10, then closing the door 8 open taps 18 and 19 and when manometer 21 shows an equal 5 pressure of the air as manometer 23, close taps 18 and 19, open hatch 11 and the exit for the crew in diving dresses is clear.

Life saving apparatus can be kept on the boat, which when unfastened comes up with 10 the crew, who thus are saved.

If the submarine vessel is in good condition, but owing to some circumstances must be left for some time under water, a part or the entire crew can leave the vessel and 15 returning afterwards can continue the work of salvage on the vessel.

The entrance back into the body, when it is submerged is performed in the same way, closing the hatch 11 and opening taps 25, 20 the air from compartment 2 and 3 flows through pipes 24 into the compartment 7, and when the pressure of the air is equal everywhere the door is opened without difficulty.

25 After reentering the vessel it sometimes happens that there is an excessive pressure of air in the inner compartments of the submarine. To remedy this, electrocompressor 16 is started to pump out the excessive 30 amount of the air from the compartment back into the tank 15, filling the tank 15

for further operations, and by the same way filtering the air in the submarine vessel.

The embodiment of the invention is shown in the drawings, and set forth in the specification, but it will be understood that any modification within the scope of the claim may be made in the construction without departing from the principle of the invention or sacrificing any of its advantages. 40

I claim:

An escape means for submarines, comprising a main hull compartment, an upper conning tower compartment with an adjacent diver's compartment, and an escape passage 45 communicating with the latter by a hatch door, doors for affording communication between the conning tower compartment and the main and diver's compartments, an air tank in the main compartment, an electric 50 air pump for supplying air thereto, an air pipe leading from the tank provided with valved connections to the escape passage and the two upper compartments, a valved connection between the tower and main compartment and air manometers for indicating the air pressure in the upper compartments and the escape passage substantially as described.

In testimony whereof I affix my signature 60 hereto.

WASSYL ORLOWSKY.
